US00D601436S

(12) **United States Design Patent**
Stephens et al.

(10) **Patent No.:** **US D601,436 S**
(45) **Date of Patent:** **** *Oct. 6, 2009**

(54) **CONTAINER BODY**

(75) Inventors: **Jo Stephens**, Chicago, IL (US);
Jonathan P. Meyer, Chicago, IL (US)

(73) Assignee: **Rexam Beverage Can Company**,
Chicago, IL (US)

(*) Notice: This patent is subject to a terminal disclaimer.

(**) Term: **14 Years**

(21) Appl. No.: **29/321,711**

(22) Filed: **Jul. 22, 2008**

(51) LOC (9) Cl. **09-02**

(52) U.S. Cl. **D9/772**

(58) **Field of Classification Search** D9/500,
D9/501, 503, 504, 763, 766, 767, 772, 776,
D9/777, 778, 779, 780; 215/253-258, 273,
215/274; 220/62.12, 254.1, 258.3, 259.3,

(57) **CLAIM**

I claim the ornamental design for a container body, as shown and described.

DESCRIPTION

FIG. 1 is a perspective view of the present invention;

FIG. 2 is a side view of the present invention;

FIG. 3 is a top view of the present invention; and,

FIG. 4 is a bottom view of the present invention.

Features shown in broken lines in the drawings are not part of the claim.
